US00D935025S

(12) **United States Design Patent** (10) **Patent No.:** **US D935,025 S**
(45) **Date of Patent:** **** Nov. 2, 2021**

(54) **HELICAL IMPLANT**

(71) Applicant: **Orthocision Inc.**, Folsom, CA (US)

(72) Inventors: **Troy Schifano**, Morgantown, WV (US);
Steve Anderson, Folsom, CA (US)

(**) Term: **15 Years**

(21) Appl. No.: **29/777,534**

(22) Filed: **Apr. 7, 2021**

Related U.S. Application Data

(62) Division of application No. 29/630,686, filed on Dec. 22, 2017, now Pat. No. Des. 921,898.

(57) **CLAIM**

We claim the ornamental designs for a helical implant, as shown and described.

DESCRIPTION

FIG. 1 is a perspective front view of the helical implant; FIG. 2 is a perspective top view of the helical implant of FIG. 1; FIG. 3 is a perspective bottom view of the helical implant of FIG. 1; FIG. 4 is a side view of a first side of the helical implant of FIG. 1; FIG. 5 is a side view of a second side of the helical implant of FIG. 1; FIG. 6 is a side view of a third side of the helical implant of FIG. 1; FIG. 7 is a side view of a forth side of the helical implant of FIG. 1; FIG. 8 is a top view of the helical implant of FIG. 1; FIG. 9 is a bottom view of the helical implant of FIG. 1; FIG. 10 is a perspective front view of a first alternative embodiment of the helical implant; FIG. 11 is a perspective top view of the helical implant of FIG. 10; FIG. 12 is a perspective bottom view of the helical implant of FIG. 10; FIG. 13 is a side view of a first side of the helical implant of FIG. 10; FIG. 14 is a side view of a second side of the helical implant of FIG. 10; FIG. 15 is a side view of a third side of the helical implant of FIG. 10; FIG. 16 is a side view of a forth side of the helical implant of FIG. 10; FIG. 17 is a top view of the helical implant of FIG. 10; and, FIG. 18 is a bottom view of the helical implant of FIG. 10. The broken lines in the drawings illustrate portions of the helical implant which form no part of the claimed design

1 Claim, 8 Drawing Sheets
